UNITED STATES PATENT OFFICE.

KERON J. HOLLAND AND GAYUS D. WEBB, OF JOLIET, ILLINOIS.

HEADLIGHT DIMMER.

Application filed February 24, 1923. Serial No. 621,047.

To all whom it may concern:

Be it known that we, KERON J. HOLLAND and GAYUS D. WEBB, citizens of the United States, residing at Joliet, in the county of Will and State of Illinois, have invented certain new and useful Improvements in Headlight Dimmers, of which the following is a specification.

This invention relates to automobiles, and 10 has special reference to a headlight for automobiles.

It is a well recognized fact that the laws of various States require certain definite restrictions to be made for the purpose of 15 preventing glare from automobile headlights.

One important object of the invention is to provide an improved and simplified form of general construction of headlight for the 20 prevention of glare.

A second important object of the present invention is to provide an improved and novel form of headlight reflector wherein the reflecting surfaces will be of two different 25 characters so that while an intense beam of light may be reflected from the central part of the reflector, the outer parts of such reflector will be so constructed as to throw a soft and mellow light in the nature 30 of a flood light.

A third important object of the invention is to provide, in combination with a reflector as described above, a screen capable of being interposed in the beam of 35 bright light so as to render the latter also mellow and soft, thus giving a very considerable quantity of light without producing a glare.

With the above and other objects in view 40 as will be hereinafter apparent the invention consists in general of certain novel details of construction and combinations of parts hereinafter fully described, illustrated in the accompanying drawings and specifically claimed.

In the accompanying drawings like characters of reference indicate like parts in the several views, and:

Fig. 1 is a vertical longitudinal section 45 through a head light constructed in accordance with this invention.

Fig. 2 is a plan view thereof, the view being partly broken away, and partly diagrammatic, in order to more fully illustrate 50 the invention.

In the embodiment of the invention herein illustrated, there is shown a housing or casting 10, which is of any preferred form of construction proper to accommodate the peculiar reflector and its parts as used here-with. The reflector preferably is formed with a metallic body 11 having an inner surface of parabolic longitudinal section. In the axis of the paraboloid thus formed, there is placed the usual lamp socket 12 carrying a lamp 13, the filament of which is located at the focus of the reflector. It is preferred that the paraboloid forming the reflector be of great length compared to its focal distance for reasons that will be hereinafter explained. The central portion of this reflector is plated with some such substance as nickel or the like, which is capable of being highly polished so as to reflect practically all of the rays of light striking it and, owing to the shape of this reflector, the rays of light from the lamp 13 which strike the reflector will be reflected as practically parallel rays, it being obvious that a slight error will exist in the parallelism by reason of the fact that the filament is of definite dimensions and not a point. Beyond the polished reflecting surface 13', the reflector is lined as at 14 with white enamel or glass, it being understood that the glass used is preferably of the type known as opal glass. Such a surface reflects a great deal of the light striking on it, but at the same time the reflected light is greatly softened and glare is prevented.

Thus it will be seen that this type of reflector projects a central brilliant beam surrounded by a marginal ring of soft light. The reflector is provided at its base with a flange 15, and is closed in front by a glass 16 secured in position by the usual ring 17 attached to the body 10 by screws 18. Vertically below the axis of the reflector there is provided a foot step bearing 19 which receives the point of a pintle 20 supporting a revoluble disk 21 of white or opal glass or other like material. The upper end of this disk 21 is connected to an operating shaft 22. The diameter of the disk 21 is greater than the greatest diameter of the metal plated part of the reflector, so that when the disk is turned to a position perpendicular to the axis of the reflector, all the light rays from the lamp 13 which are reflected by the reflector plating 13' will strike the disk 21 and,

owing to the translucent nature of such disk, will be softened so that no glare will be caused by the central brilliant beam with the disk 21 in such position. Moreover, the 5 length of the paraboloid is such that no light rays can pass directly from the lamp 13 out of the reflector except the disk 21 is turned to lie with its equatorial axis in the axis of the reflector.

10 It will be obvious that a variety of means may be used for the purpose of rotating the disk between its two positions, and that such means may be operated by the driver of the automobile from his seat. As one example of such operating means, though not necessarily the only manner in which the operating means may be effected, there is here shown a double armed lever 23 fixed 15 on the upper end of the shaft 22. At 24 are shown two solenoids, each having a core 25 connected to a respective arm of the double armed lever by a pin and slot connection as shown at 26. One end of each of these solenoids is grounded, preferably on 20 the casing 10, as at 27. From the other end of each solenoid leads a connecting wire 28, each of these wires being connected to a contact 29. At 30 is a switch arm which is capable of being swung from one to the 25 other of the contacts 29, and which is connected by wire 31 to the usual battery 32 of the automobile, this battery being grounded in the ordinary manner as at 33. The switch 30 is located convenient to the 30 operator of the automobile, and it will be obvious that by swinging the switch to one or the other of the contacts 29, energization of a respective solenoid 24 will be effected. For instance, in Fig. 2, it is seen 35 that the lower solenoid 24 has been energized, and that consequently, the disk 21 is placed across the path of the beam of light from the reflecting surface 13. If now the switch 30 is to be turned to the other contact 29, the upper solenoid 24 will be energized and the disk 21 will be swung edge- 40 ways to the beam of light from the reflecting surface 13, thus permitting practically all of said light to pass as a brilliant beam, 45 said disk being of slight thickness.

50 It will be obvious that a variety of reflecting surfaces may be employed, the essential features of the two surfaces being that the central surface should be adapted to reflect practically all of the rays of light without diffusion while the outer surface 14 should be adapted to diffuse and soften the rays of light striking it. In like manner, it will be obvious that the screen or disk 55 21 may be made of other material than white or opal glass, it being only essential that such screen should be a translucent diffusing and softening screen.

While we have stated that the outer re-

flecting surface is of enamel or opal glass, 60 it will be obvious that, since the purpose of this surface is to soften and diffuse the light striking it, other material may be used as a coating, such for instance as dull porcelain, powdered aluminum or the like, 70 it being merely necessary that the surface shall be a softening and diffusing surface.

75 There has thus been provided a simple and efficient device of the kind described and for the purpose specified.

It is obvious that minor changes may be made in the form and construction of the invention without departing from the material spirit thereof. It is not, therefore, desired to confine the invention to the exact 80 form herein shown and described, but it is desired to include all such as properly come within the scope claimed.

Having thus described the invention, 85 what is claimed as new, is:

1. In an automobile headlight, a parabolic reflector having a central portion of high reflective power adapted to reflect practically all light impinging upon it, an outer portion adapted to reflect light impinging upon it in a softened and diffused manner, and a softening and diffusing screen of greater diameter than the central portion and of less diameter than the outer portion of the reflector, said screen being mounted in said reflector between the focus and the open end of the reflector and arranged to swing between a position at right angles to the axis of the reflector and a position edgewise to the light from the central portion of said reflector.

2. In a device of the kind described, a parabolic reflector having a lamp located at its focus, the central portion of said parabolic reflector having a reflecting surface of highly polished metal, the outer portion of said parabolic reflector having a reflector surface adapted to diffuse and soften rays from the lamp impinging thereon, and a diffusing and softening disk rotatably mounted in the reflector between the lamp and the outer end of the reflector and having a diameter greater than the highly polished portion of said reflector and of less diameter than the section of the reflector in which it is placed, said disk being adapted to swing between a position transverse the beam of light from the highly polished reflector to a position edgewise of said beam.

3. In a device of the kind described, a parabolic reflector having a lamp located at its focus, the central portion of said parabolic reflector having a reflecting surface of highly polished metal, the outer portion of said parabolic reflector having a reflector surface adapted to diffuse and soften rays from the lamp impinging thereon, and a diffusing and softening disk rotatably

nounted in the reflector, between the focus and the open end of the reflector, and having a diameter greater than the highly polished portion of said reflector, said disk being adapted to swing between a position transverse the beam of light from the highly polished reflector to a position edgeways of

said beam, said disk being constructed of opal glass.

In testimony whereof we affix our signatures.

KERON J. HOLLAND.
